LADY'S HANDBAG

Llewellyn Bley, Ridgefield Park, N. J., assignor to Llewellyn, Inc., New York, N. Y.

Application October 29, 1951, Serial No. 17,162

Term of patent 7 years

(Cl. D87—3)

To all whom it may concern:

Be it known that I, Llewellyn Bley, a citizen of the United States, residing at Ridgefield Park, in the county of Bergen and State of New Jersey, have invented a new, original, and ornamental Design for a Lady's Handbag, of which the following is a specification, reference being had to the accompanying drawing, forming a part thereof.

Fig. 1 is a front elevational view of a lady's handbag, showing my new design.

Fig. 2 is a top plan view thereof, with the handle tilted from the upright position.

Fig. 3 is a side elevational view thereof.

Fig. 4 is a fragmentary sectional view taken on line 4—4 of Fig. 2.

I claim:

The ornamental design for a lady's handbag, substantially as shown.

LLEWELLYN BLEY.
